Daniel Hoyt

UNITED STATES PATENT OFFICE.

DANIEL HOYT, OF SOUTH NORWALK, CONNECTICUT.

SASH-LOCK.

SPECIFICATION forming part of Letters Patent No. 651,570, dated June 12, 1900.

Application filed August 21, 1899. Serial No. 727,902. (No model.)

To all whom it may concern:

Be it known that I, DANIEL HOYT, a citizen of the United States, and a resident of South Norwalk, in the county of Fairfield and 5 State of Connecticut, have invented certain new and useful Improvements in Sash-Locks, of which the following is a specification.

The object of my invention is to produce a simple sash-lock by which the sash may be 10 made to stay and be locked in any position and which cannot be forced without breaking, and it is especially adapted for railway-trains, as the sash will not jar down with the motion of the train.

15 Figure 1 is a view, partly in section, showing my improved fastener placed on a window-sash. Fig. 2 is an enlarged section of the fastener. Fig. 3 is a plan view of the same.

The fastener consists of a casing *a*, between 20 the sides of which are pivoted levers *b*, the levers being of such shape and pivoted in such a manner that as their ends are moved from each other the bearing-surfaces will be caused to engage more firmly with the window-sash. The shape is generally that of a cam of increasing radius. The ends of the levers are normally kept apart by a leaf-spring *c*. On the end of one of the levers is a link *d*, adapted to engage with the notch *e* in the other 25 lever, whereby the ends of the two levers may be kept together, thus keeping the fastener out of the locking position. The faces of these cams are corrugated, as clearly shown. Secured to the window-frame in any suitable 30 manner is a strip of metal *f*, the surface of which is corrugated, as shown, to correspond to the corrugations on the locking-pieces. These corrugations are made of any desired 35 shape or size. In small windows the corrugations are preferably close together. It will be obvious that as the ends of the levers are 40 brought close to each other the sash can be

moved up and down freely. Upon letting go of the levers the cams will bear against the corrugated strip and lock the sash securely 45 in position. Any tendency of the sash to move either up or down will of course cause one or the other of the levers to bind more firmly.

By this construction not only do I secure a 50 fastener which will keep the sash in any position, but also one which will lock the sash in such manner that it cannot be forced open without breaking the fastener, and I also avoid injury to the wood of the window-frame. 55 In that style of lock where the cam bears directly on the wood of the frame it will of course take but a comparatively-short time to wear the wood, so that the sash can be moved up and down, notwithstanding the 60 locking devices, with but comparatively little effort.

What I claim, and desire to secure by Letters Patent, is—

In a sash-fastener the combination of a casing adapted to be secured to the sash, levers pivoted in said casing, said levers having corrugated cam-surfaces, a strip of metal on the window-frame having a surface corrugated to correspond with the corrugations of the 70 cams, whereby said sash may be locked in any position, and means for keeping the operating ends of the levers normally apart, a link carried by one arm and a notch on the other for engaging said link, substantially as 75 described.

Signed at the city of New York, in the county of New York and State of New York, this 16th day of August, A. D. 1899.

DANIEL HOYT.
